RAILWAY SIGNALING

Original Filed Oct 15, 1925

UNITED STATES PATENT OFFICE

EDWARD C. SASNETT, OF WASHINGTON, DISTRICT OF COLUMBIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed October 15, 1925. Serial No. 62,542. Renewed August 27, 1928.

This invention relates to railway traffic controlling systems and has particular reference to an automatic train control system of the continuous indication type, comprising traffic controlled means for transmitting from the track rails through a vehicle carried translating device energy in the form of electrical impulses, the character or frequency of the impulses being varied in accordance with traffic conditions, and signals or train control mechanism selectively governed by the impulses in accordance with the particular code of impulses received.

An object of the invention is to provide a system of this character in which the codes of impulses are generated at a single station and transmitted to the track rails through line wires or otherwise. By generating the impulses at a single station, I eliminate separate coding devices for each block of the track and therefore very materially simplify the apparatus while rendering the codes absolutely uniform throughout the system.

Another object is to provide a code system of train control employing insulated blocks without the necessity of track relays. For the attainment of this object I provide a system in which the impulses are applied to the rails at the exit ends of the blocks and are transmitted to the next block in rear, preferably through synchronously closed shunts around the insulation joints. Obviously, the elimination of the track relays reduces the system to minimum simplicity and moreover increases the safety factor.

A still further object is to provide a code system in which the codes consist of alternating current impulses of different frequencies. For example, the clear code may consist of impulses of three different frequencies periodically transmitted; a more restrictive code, of impulses of two frequencies, and a still more restrictive code, of impulses of the same frequency.

Where the system is used without track relays and with or without insulated joints in the track rails, these codes are produced by periodically supplying to the rails at longitudinally spaced points alternating currents of differ-

ent frequencies, respectively, whereby a vehicle on the track provided with translating devices respectively responsive to the different frequencies will have all, some or none of its translating devices periodically energized according to the conditions of traffic. The impulses of different frequencies may be, but are not necessarily, transmitted asynchronously.

The invention will be particularly described with reference to the accompanying drawings, which show diagrammatically one embodiment thereof, and the novel features of the invention will be set forth in the claims.

The particular system chosen for illustration comprises a stretch of track divided into insulated blocks A, B, C, D, E etc., over which the direction of traffic is assumed to be from left to right, although the system is equally well adapted for traffic in the opposite direction. Relays 10^a, 10^b, 10^c, 10^d, 10^e, etc. are located adjacent the junctions of the blocks and are connected to the secondaries of transformers 11, the primaries of which are connected to line wires 12 extending from a station throughout the signalled territory. At this station, switches 13, 14 and 15 are operated successively and periodically to connect sources of alternating current 16, 17 and 18 across the line wires 12. As illustrated, switches 13, 14 and 15 are operated respectively by cams 19, 20 and 21 which are rigid with a worm wheel 22 driven by a worm 23 fixed to the armature 24 of a motor. The raised portions of cams 19, 20 and 21 are angularly displaced and may extend through any desired arc, so that the switches are successively closed during each revolution of the cam shaft. The alternators 16, 17 and 18 are intended to deliver currents of suitably different frequencies of low orders and not harmonically related.

Relays 10^b and 10^e and corresponding relays throughout the system are made selectively responsive to the frequency of alternator 16; relays 10^a and 10^d are responsive to the alternator 18; and relays 10^c and corresponding relays are responsive to alternator

17. That is to say, the relays are arranged in groups of three, relays of the same group being responsive to different frequencies and corresponding relays of the several groups being responsive to the same frequency. Relays 10^b, 10^c and 10^d constitute one group, being respectively responsive to the frequencies of alternators 16, 17 and 18. Relay 10^e is the first of the following group and relay 10^a is 10 the last of the preceding group.

It will now be clear that when the alternator 16 is connected to the line wires, relay 10^b, and corresponding relays throughout the system will close their front contacts and 15 open their back contacts, and that relays 10^c and 10^d are similarly operated respectively when alternators 17 and 18 are connected across the line wires. It will be observed that when the front contacts of the relays are 20 closed the secondaries of the transformers are connected across the rails and the shunts around the insulated joints through the back contacts of the relays are opened. As is customary, resistances R may be inserted in the 25 conductors connecting the secondaries of the transformers to the track rails to prevent dead short circuiting of the transformers by the wheels and axles of the vehicles.

The track system above described is adapted to control the display of signals on the track or on the cab of a locomotive, or on both. The drawing shows cab signals only, a vehicle being indicated in block B provided with signaling apparatus responsive selectively to the current impulses flowing in the track rails. The vehicle is provided with a coil 25 carried adjacent the rails so as to have electromotive forces induced therein by the track currents. Coil 25 is connected to a suitable amplifying device 26, whereby the feeble currents picked up from the track are amplified and delivered to relays 27, 28 and 29, which are made selectively responsive to the frequencies of alternators 16, 17 and 18. The 40 amplifying device 26 may include an amplifier for each frequency, as is old and well known in the art.

In the instantaneous positions of the parts shown by the drawing, alternator 16 is connected to the line wires by switch 15, and relays 10^b and 10^c are accordingly energized. Current is flowing from the secondary 11 through the front contacts of relay 10^c, through the track rails of block D, through 50 the shunts around the insulated joints between blocks D and C, closed at back contacts of relay 10^c, through the rails of block C, through the shunts around the insulated joints between blocks C and B, closed at 55 the back contacts of relay 10^c, through the rails of block B, and through the wheels and axles of the vehicle. This current has the frequency of alternator 16, and accordingly the relay 27 on the vehicle is energized. When 60 switch 15 opens and switch 13 closes alternator 18 will be connected to the line wires and relay 10^e will drop and relay 10^d will pick up. Current from alternator 18 will now flow through the front contacts of relay 10^d from the secondary of transformer 11, through the 65 rails of block C, through the shunts around the insulated joints between blocks C and B, and through the wheels and axles of the vehicle. Relay 29 on the vehicle will accordingly be energized. When switch 13 opens and switch 14 closes current from alternator 18 will be cut off and current from alternator 17 will flow through the front contacts of relay 10^e, through the rails of block B and through the wheels and axles of the vehicle, so 70 causing the cab carried relay 28 to pick up.

From the foregoing, it will be understood that under normal, or clear conditions, the vehicle carried coil 25 will pick up successively currents of the frequencies of alternators 16, 17 and 18.

Suppose now that with the vehicle shown in block B, there should be an advance vehicle in block D. It will be obvious that the vehicle in block B can receive current only 90 from the operations of relays 10^c and 10^d. As this current is in impulses of the frequencies of alternators 17 and 18, the cab relays 28 and 29 will be intermittently energized, but relay 27 will be continuously deenergized.

If with the vehicle in block B there should be an advance vehicle in block C, the vehicle in block B could receive current only from the operation of relay 10^c. This current would be in the form of impulses of the frequency of alternator 17. Hence under these conditions, the cab relay 28 would be intermittently energized, but relays 27 and 29 would remain continuously deenergized.

Under clear conditions therefore, relays 27, 28 and 29 are successively and periodically energized. Under caution conditions, only two of the cab relays will be intermittently energized. The relays that will be intermittently energized under caution conditions may be 27 and 28, or 28 and 29, or 27 and 29, depending upon the particular two frequencies received and therefore depending upon the particular pairs of relays 10 between the vehicles. Under danger conditions, only one of the relays 27, 28 or 29 will be intermittently energized. It may be any one of the relays, as will be obvious.

Any suitable signaling mechanism may be provided selectively controlled by the relays 27, 28 and 29. As shown, relay 27 controls a slow release relay 30; relay 28, a slow release relay 31; and relay 29, a slow release relay 32. These relays control the circuits of a clear signal lamp 33, a caution signal lamp 34 and a danger signal lamp 35.

Under clear conditions the slow release relays 30, 31 and 32 are continuously held up, as the interval between successive energizations of each is only two seconds. Hence 100

under clear conditions, the circuit of lamp 33 is closed through the upper front contacts of relays 30, 31 and 32.

Under caution conditions, only two of the relays 30, 31 and 32 are intermittently energized. Hence the circuit of the clear lamp is interrupted at a front contact of one of these relays. If relays 30 and 31 are the pair intermittently energized, the circuit of the caution lamp 34 will be closed through front contacts 36 and back contacts 37. If 28 and 29 are intermittently energized, the circuit of this lamp will be closed at back contacts 38 and front contacts 39. If relays 30 and 32 are intermittently energized, the circuit of said lamp will be closed at front contact 40, back contact 41 and front contact 42.

Under danger conditions, only one of the relays is intermittently energized. If this one is 30, the circuit of danger lamp 35 will be closed through front contact 43 and back contacts 44; if 31, the circuit will be closed through front contact 45 and back contacts 46 and 47; if 32, the circuit will be closed through front contact 48 and back contacts 49.

Altho I have particularly described a single system embodying my invention it will be obvious to those skilled in the art that the principles of the invention can readily be embodied in systems of various constructions and I therefore do not intend to limit my invention except as defined in the claims.

I make no claim, in this application to the combination of means for supplying coded or periodically varied current to the trackway and train carried means controlled by said trackway current and including slow acting means for bridging the intervals between periodic variations in such current, which combination forms the subject matter of application Ser. No. 215,318, filed August 25, 1927, by Arba G. Williamson.

I claim:

1. A railway signaling system, comprising a track divided into insulated blocks, means for periodically connecting a source of current across the rails at the exit end of a block and synchronously connecting a shunt around an insulated joint at the entrance of said block, whereby current from said source is transmitted to the block in the rear, a translating device responsive to current flowing through the rails, and signaling means controlled by said translating device.

2. A railway signaling system, comprising a stretch of track, means for periodically and successively connecting sources of current across the track at a plurality of spaced points, said means comprising a relay at each of said points and means at a single station controlling said relays, translating devices responsive to energy flowing through the track rails, and signals selectively actuated by said translating devices in accordance with

the number of points from which energy is transmitted thereto.

3. A railway signaling system, comprising a stretch of track, means for periodically and successively connecting sources of current across the track rails at a plurality of spaced points, said means comprising a relay at each of said points, a line wire to which the relays are connected, and switch mechanism periodically and successively connecting currents of different character to said line wire, translating devices responsive to energy flowing through the track rails, and signals selectively actuated by said translating devices in accordance with the number of points along the track from which current is transmitted thereto.

4. A railway signaling system comprising a stretch of track, means for periodically and successively transmitting current of different character through the track rails from a plurality of spaced points along the track, said means comprising a relay at each of said points, a line wire to which the relays are connected, and periodically operating switch mechanism connected to said line wire, translating devices responsive to energy flowing through the track rails, and signals selectively controlled by said translating devices in accordance with the character of current transmitted through the rails to said translating devices.

5. A railway signaling system, comprising a stretch of track, means for periodically and successively connecting electrical energy across the track rails at a plurality of spaced points, said means comprising selectors at each of said points and means at a single station controlling said selectors, translating devices responsive to energy flowing through the track rails, and signals controlled by said translating devices.

6. A railway signaling system, comprising a stretch of track, means for periodically and successively connecting electrical energy across the track rails at a plurality of spaced points, said means comprising selectors at each of said points and means at a single station controlling said selectors, translating devices responsive to energy flowing through the track rails, and signals controlled by said translating devices and selectively actuated in accordance with the number of points from which energy is transmitted thereto.

7. In a railway signaling system, a track divided into insulated blocks, means for successively and periodically connecting alternating energy of different frequencies across the rails at the exit end of each block, and signaling mechanism selectively responsive to said frequencies.

8. In a railway signaling system, a stretch of track, means for successively and periodically connecting alternating energy of different frequencies across the track rails at

spaced points, and signaling mechanism for the stretch selectively responsive to said frequencies.

9. In a railway signaling system, a track divided into insulated blocks, means for successively and periodically applying to the track rails of a block alternating energy of three frequencies under clear traffic conditions, two frequencies under caution conditions, and one frequency under danger conditions, a translating device, selectively responsive to said frequencies and clear, caution and danger signals actuated by said translating devices.

10. In a railway signaling system, a track divided into insulated blocks, line conductors, means at a central station for connecting to said conductors successively and periodically sources of alternating currents of different frequencies, a relay for each block connected to said conductors, said relays being arranged in groups with relays belonging to the same group respectively responsive to currents of different frequencies and with corresponding relays of the several groups responsive to current of the same frequency, said relays when energized connecting said conductors across the track relays at the exit ends of the blocks, and means permitting current to flow from said conductors through the rails of a number of blocks preceding any blocks across which the conductors are connected by an energized relay, said number being one less than the number of relays constituting a group.

11. In a railway signaling system, a track divided into insulated blocks, sources of currents of different characters, selectors associated with each block operated from a single station for connecting said sources successively and periodically across the rails at the exit end of each block, a translating device selectively responsive to said currents and signaling mechanism controlled by said translating device.

12. In a railway signaling system a track divided into insulated blocks, sources of currents of different frequencies, selectors associated with each block operated from a single station for connecting said sources successively and periodically across the rails at the exit end of each block, a vehicle travelling on the track, translating devices on the vehicle selectively operated in accordance with the frequencies of the current received and signaling mechanism controlled by said translating devices.

13. In a railway signaling system, a vehicle travelling on a track, translating devices on the vehicle, means for transmitting to said translating devices alternating currents of two frequencies alternately and at brief intervals, whereby said translating devices are intermittently energized under predetermined traffic conditions, and a signal held

at one indication only so long as said translating devices are thus energized.

14. A railway signaling system comprising a wayside conductor, selective means controlled from a central station for connecting electrical energy to said conductor at spaced points, said selective means being arranged in successive groups and in the same group operating to connect energy to said conductor successively, a vehicle having a translating device responsive to current flowing through said conductor, and train governing mechanism selectively controlled in accordance with the number of points from which energy is transmitted to said translating device. 70 75

15. A railway signaling system comprising a wayside conductor, frequency selective relays located at spaced points along the trackway connected to a line wire leading to a central station, means for periodically connecting alternating currents of different frequencies to said line wire to selectively energize said relays, said relays when energized connecting electrical energy to said conductor at spaced points thereon, a vehicle having a translating device responsive to currents flowing through said conductor and train governing mechanism controlled by said translating device. 80 85 90

16. A railway signaling system comprising a wayside conductor, selective devices controlled from a central station for connecting electrical energy to said conductor at spaced points, said selective devices being arranged in successive groups and in the same group transmitting energy to said conductor successively and corresponding devices in the several groups transmitting energy to said conductor synchronously, a vehicle having a translating device responsive to energy flowing through said conductor, and train governing mechanism controlled by said translating device. 95 100 105

17. A railway signaling system comprising a stretch of track, selective devices controlled from a central station for connecting electrical energy across the track rails at spaced points, said devices being arranged in successive groups and in the same group transmitting energy to said rails successively and corresponding devices in the several groups transmitting energy to said rails synchronously, a vehicle having a translating device responsive to energy flowing through said rails, and train governing mechanism controlled by said translating device. 110 115 120

18. A railway signaling system comprising a stretch of track, a line wire leading to a central station, frequency selective devices connected to said line wire and adapted to transmit energy to the track rails at spaced points, said devices being arranged in successive groups and in the same group transmitting energy to the rails successively, means at the central station for successively and period-

ically connecting sources of alternating current of different frequencies to said line wire, and train governing devices responsive to energy flowing through the rails.

5 19. A railway signaling system comprising a wayside conductor, a vehicle having a translating device responsive to current flowing through said conductor, a line wire leading to a central station, frequency selective devices connected to said line wire and adapted to transmit energy to said conductor at spaced points, said selective devices being arranged in successive groups and in the same group adapted to transmit energy of different frequencies, and means at the central station for successively and periodically connecting sources of alternating current of different frequencies to said line wire. 70

10 20. A railway signaling system comprising a track divided into insulated blocks, means for periodically connecting electrical energy across the rails at the exit end of a block, means for transmitting said energy to the rails of the block immediately in rear, and signaling means responsive to said energy. 75

15 21. A railway signaling system comprising a track divided into insulated blocks, means for each block operating to connect energy intermittently across the rails at the exit ends 80 of the blocks, said means operating to connect energy asynchronously in the case of a plurality of successive blocks, means for transmitting energy from one block to the block immediately in rear thereof, and a vehicle 85 travelling on the track having a translating device responsive to said energy. 90

20 22. A railway signaling system comprising a track divided into insulated blocks, shunts around the insulated joints defining the blocks, means for periodically connecting electrical energy across the rails at the exit ends of the blocks, said means being arranged in successive groups and in the same group operating to connect energy across the rails 95 successively while corresponding means of the several groups operate to connect energy across the rails synchronously, each of said means when operating to connect energy across the rails opening the shunt around the adjacent insulated joint, and a vehicle travelling on the track having a translating device responsive to said energy. 100

25 23. A railway signaling system comprising a stretch of track, a line wire leading to a central station, selective relays connected to said line wire at spaced points, said relays being arranged in successive groups and in the same group adapted to operate successively, means at the central station controlling said relays, electrical connections to the track rails controlled by said relays, and train governing devices responsive to energy flowing through the rails. 110

30 24. A railway signaling system comprising a stretch of track, selective devices at spaced

points along the track controlled from a central station, electrical connections to the track rails controlled by said devices, said devices being arranged in successive groups and in the same group operating successively, and train governing devices responsive to energy flowing through the rails. 125

25 25. A railway signaling system comprising in combination with a stretch of track divided by insulated joints into blocks, means for connecting electrical energy across the track rails at the exit ends of the blocks, means for periodically bridging said insulated joints, a vehicle having a translating device responsive to current flowing in the rails, and train governing means controlled by said translating device. 130

30 26. A railway signaling system comprising a track divided by insulated joints into blocks, means for connecting electrical energy across the track rails of the several blocks, means for periodically bridging said insulated joints, said means operating to bridge adjacent insulated joints asynchronously, a vehicle having a translating device responsive to current flowing in the rails, and train control mechanism governed by said translating device. 135

35 27. A railway signaling system comprising in combination with two sections of track divided by an insulated joint, means for connecting electrical energy across the track rails at the exit ends of each section, means for periodically bridging the insulated joint between said sections, whereby energy is transmitted from the forward section to the rear section, and a vehicle having train control mechanism responsive to the currents flowing in the track rails. 140

40 28. In a railway traffic controlling system, in combination, a stretch of track, line wires extending along said track, electrical connections between the line wires and track at longitudinally spaced points thereof, a source of energy, and constantly operating switch mechanism controlling the connection of said source of energy to said line wires, whereby periodic current impulses are produced in said wires and in said track. 145

45 29. In a railway traffic controlling system, in combination, a stretch of track divided into insulated blocks, line wires extending along said track, electrical connections between the line wires and the exit ends of the blocks, a source of energy adapted to be connected to said line wires, and constantly operating switch mechanism controlling the application of energy to said wires, to cause current impulses in the line wires and track 150 rails. 155

50 30. In a railway traffic controlling system, a stretch of track divided into insulated blocks, sources of current of different frequencies, and means for connecting said sources alter- 160

nately and periodically across the track rails at the exit ends of the blocks.

31. In a railway traffic controlling system, in combination, a stretch of track divided into insulated blocks, a line wire extending along said track, electrical connections between said line wire and track at the exit ends of the blocks, and means for producing periodic impulses of alternating current in said line wire to cause periodic current impulses in the track rails.

32. In a railway traffic controlling system, in combination, a stretch of track divided into insulated blocks, line wires extending along said track, electrical connections between said line wires and the track at the exit ends of the blocks, a source of alternating energy, and constantly operating mechanism for controlling the application of said energy to said line wires to produce periodic impulses of alternating current in the track rails.

33. In a code continuous indication system, a stretch of track divided into insulated blocks, and means for producing a code of current impulses in the track rails, said means comprising a constantly operating coding device at a single station and means for transmitting the current impulses produced by said device to the track rails of the several blocks of said stretch.

34. A railway traffic controlling system comprising, in combination, a stretch of track divided into insulated blocks, line wires extending along the track, sources of current of different frequencies, constantly operating means for periodically controlling the application of said sources to the line wires, means adjacent the block junctions for selectively transmitting the alternating currents flowing in the line wires to the track rails, a vehicle travelling on the track having translating devices selectively actuated by said currents and train control devices governed by said translating devices.

35. A railway traffic controlling system comprising, in combination, a stretch of track, line wires extending along the track, sources of current of different frequencies, constantly operating means for controlling the application of said sources to the line wires, frequency selective devices for transmitting the alternating currents flowing in the line wires to the track rails, a vehicle travelling on said track having translating devices selectively actuated by said currents, and train control devices governed by said translating devices.

36. In a railway traffic controlling system having a stretch of track including an insulated block, line wires extending along the track, a source of alternating current, constantly operating means for periodically applying said source to the line wires, a frequency selective device connected to the line

wires adjacent the exit end of the block adapted to transmit said alternating current to the track rails, a vehicle travelling on the track having a coil disposed in inductive relation to the rails, a frequency selective translating device connected to said coil, and train control means governed by said translating device.

37. In a code continuous indication system, a stretch of track and means for intermittently connecting sources of current across the track rails at longitudinally spaced points thereof to produce codes of impulses in the track rails, said means comprising a constantly operating coding device at a single station which controls the application of energy to the rails throughout the system.

38. In a code continuous indication system, a stretch of track and means for intermittently connecting sources of current across the track rails at longitudinally spaced points thereof to produce codes of impulses in the track rails, said means comprising a constantly operating coding device at a single station and selective devices at longitudinally spaced points of the track governed by said coding device, said selective devices governing the application of energy to the track rails.

39. In a railway traffic controlling system, in combination, a stretch of track, line wires extending along the track, sources of current of different frequencies, constantly operating mechanism for periodically controlling the application of said sources to the line wires, and frequency selective means at spaced points along the track for selectively transmitting the alternating currents flowing in the line wires to the track rails.

40. In automatic train control system, in combination with a stretch of track, means for intermittently applying to the rails of said stretch at longitudinally spaced points thereof alternating currents of different frequencies, a vehicle having translating devices respectively responsive to said frequencies, and signals selectively controlled by said translating devices.

41. In an automatic train control system, in combination with a stretch of track, means for periodically applying to the rails of said stretch at longitudinally spaced points thereof alternating currents of different frequencies, a vehicle having translating devices respectively responsive to said frequencies, slow release relays respectively controlled by said translating devices, and train control mechanism governed by said relays.

42. A code-continuous-indication system comprising in combination with a stretch of track and a vehicle travelling thereon, means for periodically applying to the rails of said stretch at longitudinally spaced points alternating currents of different frequencies, so that the vehicle will receive impulses of

alternating currents of a number of different frequencies according to the number of points from which energy is transmitted thereto, and signals on the vehicle selectively controlled by said currents.

43. An automatic train control system comprising, in combination with a stretch of track, a vehicle travelling thereon, a plurality of translating devices on said vehicle, traffic controlled means for periodically transmitting through said translating devices, respectively, alternating currents of different frequencies, whereby said translating devices are periodically energized under predetermined traffic conditions, slow acting means controlled by said translating devices, and signals controlled by said slow acting means.

44. An automatic train control system comprising, in combination with a stretch of track divided into insulated blocks, traffic controlled means for applying alternating currents of different frequencies to the exit ends of the blocks periodically, a vehicle on the track having translating devices respectively responsive to said alternating currents, whereby said translating devices are intermittently energized under predetermined traffic conditions, slow release relays controlled by said translating devices, and signals governed by said slow release relays.

45. An automatic train control system comprising, in combination with a stretch of track divided into insulated blocks, traffic controlled means for periodically applying alternating currents of two different frequencies to the exit ends of the blocks under certain traffic conditions and for periodically applying alternating current of one frequency to the exit ends of the blocks under more restrictive traffic conditions, a vehicle on the track having translating devices respectively responsive to said frequencies, and signals selectively controlled by said translating devices.

46. In combination, a stretch of railway track divided into a plurality of sections, a line circuit extending along said stretch, a circuit controller comprising a periodically operated contact, means including said contact for supplying current to said line circuit, means for each section responsive to the current in said line circuit for supplying track circuit current to the rails of the corresponding section, and governing means responsive to such current.

47. In combination, a stretch of railway track divided into a plurality of sections, a line circuit extending along said stretch, means for supplying said line circuit with current periodically varying in frequency, means for supplying each section with current from said line circuit, and governing means responsive to the frequency of such current.

48. In combination, a stretch of railway

track divided into a plurality of sections, means for normally supplying each section with alternating current periodically varying in frequency, means responsive to traffic conditions for controlling the supply of such current to each track section, and train carried governing means controlled by energy received from the trackway and including a plurality of devices each selectively responsive to current of a different frequency in the trackway.

In testimony whereof I hereunto affix my signature.

EDWARD C. SASNETT.
